UNITED STATES PATENT OFFICE.

ALMON G. WARD AND GEORGE E. DAY, OF WARREN, OHIO.

DESIGN FOR A BATH-TUB LEG.

SPECIFICATION forming part of Design No. 34,976, dated August 20, 1901.

Application filed February 28, 1901. Serial No. 49,360. Term of patent 14 years.

To all whom it may concern:

Be it known that we, ALMON G. WARD and GEORGE E. DAY, citizens of the United States, residing at Warren, in the county of Trumbull and State of Ohio, have invented a new and original Design for Bath-Tub Legs, of which the following is a specification.

Our invention consists in the design illustrated in the accompanying drawing, in which 10 is shown a rounded base *a*, apparently a semi-sphere, projecting from an inverted cup *b*, grasped by bird-claws *c*, projecting downward from a leg *d*, surrounded by a raised ring *e*. Above the ring *e* the leg has a general outline 15 approaching a balloon shape, the sides *f* curving outward and upward and being connected by an outline substantially semicircular. This upper portion of the leg is ornamented by raised and depressed scrolls and curved 20 parts, as follows:

g indicates a raised panel of substantially U shape, having depressed inner portion *h*, which merges into a depression or groove *i*, of horseshoe shape, inclosed in a raised scroll 25 ornament comprising part *j*, with curved top *k*, and outwardly and downwardly curved

scrolls *l*, reaching to the sides *f*, overhanging parts *m*, having undulating surfaces and reaching to the ring *e*.

In the central upper portion of the leg is a 30 raised panel *m* with inwardly-curved sides and outwardly-curved top, flanked on each side by an undulating wedge-shaped surface *n*, outside of which on each side is a raised scroll ornament *o*, curving outward and downward and terminating in three points *p*, the parts inclosed by scrolls *o* being diversified by raised and depressed ornamentations. 35

Having thus described our invention, what we claim, and desire to secure by Letters Patent, is—

The design for a bath-tub leg, as herein shown and described.

Witness our hands, this 25th day of February, 1901, in the presence of two subscribing witnesses. 45

ALMON G. WARD.
GEORGE E. DAY.
